UNITED STATES PATENT OFFICE.

PETER WHITE, OF ST. LOUIS, MISSOURI.

STOP-BOX FOR WATER AND GAS PIPES.

SPECIFICATION forming part of Letters Patent No. 249,213, dated November 8, 1881.

Application filed July 19, 1881. (No model.)

To all whom it may concern:

Be it known that I, PETER WHITE, a resident of St. Louis, Missouri, have made a new and useful Improvement in Stop-Boxes for Water and Gas Pipes, of which the following is a full, clear, and exact description, reference being had to the annexed drawings, making part of this specification, in which—

Figure 1 is a side elevation of a stop-box having the improvement; Fig. 2, a plan; Fig. 3, a side elevation of the upper end of the box, the cover being turned up; Fig. 4, a plan, a portion of the cover being broken away to exhibit the means for locking the cover; Fig. 5, another plan, the cover being broken away at two places and turned horizontally around into a different position from that shown in Fig. 4; Fig. 6, a sectional elevation of the upper end of the box; and Fig. 7, a sectional elevation of the upper end of the box, the cover being raised.

The same letters denote the same parts.

The present improvement relates, mainly, to the construction and operation of the cover of the box.

A represents a stop-box for water and gas pipes, and, saving the present improvement, of the usual form.

B represents the cover of the box. It is circular in outline, and at its center is attached to an arm, C, the attachment being such as to enable the cover to be turned horizontally around in the top of the box. The arm C is extended and hinged to the box at c.

35 The cover has a groove, b, extending around and in its edge. The flange b', above the groove, is larger in diameter than the remainder of the cover, and when the cover is closed rests upon a ledge, a, in the top of the box. The flange b', below the groove, is notched at b², to enable that flange, as the cover is closed, to pass a stud, a', which is attached to the box upon its inner side, and projecting inwardly into the box, the operation of the improvement being as follows: To lock the box the cover B and arm C are turned down upon the hinge c, and the cover turned horizontally around upon the arm C until the notch b³ coincides with the stud a', whereupon the cover

40 falls into its seat upon the ledge a, and, as indicated in Fig. 4, the cover is then rotated

upon the arm C, so as to bring the notch b³ out of line with the stud a', for instance, as shown in Fig. 5. In this position the cover cannot be raised upon the hinge c, because of 55 the stud a' engaging in the groove b, and before the cover can be opened it has to be rotated until the notch b³ again exactly coincides with the stud a'.

The aim of the improvement is, mainly, to 60 provide means by which the box can be guarded against interference from children, who, as stop-boxes have been made, can readily open them and make trouble by filling them with dirt and stones. In the present box, from 65 having first to turn the cover around so as to exactly bring the stud and notch into coincidence before it can be raised, and from these parts being concealed when the cover is closed, the interference in question is practically prevented. The cover is purposely made so that it cannot well be operated by the hand, it having 70 two small holes, b⁴ b⁴, in its top, on opposite sides of its center, the holes being preferably too small to admit the fingers; but by inserting a suitable implement in them the operator can get sufficient hold upon the cover 75 to enable him both to rotate it and to turn it back upon the hinge c. The hinge serves also to connect the cover to the box, so that it can- 80 not be lost therefrom.

I claim—

1. The stop-box A, having the cover B and arm C, said cover at its center being attached to and rotating upon said arm, substantially 85 as described.

2. The combination of the box A, stud a', cover B, having the groove b, and flange b', notched at b², and the arm C, substantially as described.

3. The combination of the box A, having the ledge a and stud a', and the cover B, having the groove b and flanges b' and b², substantially as described.

4. The combination of the box A, having 95 the ledge a and stud a', the cover B, having the groove b and flanges b' b², and the arm C, hinged at c, substantially as described.

PETER WHITE.
